UNITED STATES PATENT OFFICE.

EDMUND C. MORGAN, OF NEW YORK, N. Y.; OLIVE EUGENIE MORGAN EXECUTRIX OF
SAID EDMUND C. MORGAN, DECEASED.

MINING SYSTEM AND APPARATUS.

Application filed June 23, 1920. Serial No. 391,213.

To all whom it may concern:

Be it known that I, EDMUND C. MORGAN, a citizen of the United States, and a resident of New York city, in the county of 5 New York and State of New York, have invented certain new and useful Improvements in Mining Systems and Apparatus, of which the following is a specification.

My invention relates to a system and apparatus for mining material, and is particularly adapted for the mining of coal.

One of the objects of my invention is the provision of improved apparatus for facilitating the mining of material, particularly 15 coal, in a mine.

A further object of the invention is the provision of improved apparatus for facilitating the mining of material and controlling the subsidence of the roof in the mine 20 chamber after the mining operations have been completed.

Another object of the invention is the provision of an improved system of mining in which the roof is supported as the 25 mining proceeds, and in which the subsidence of the roof is effected along predetermined lines and at predetermined positions and in predetermined sequence.

Another object of the invention is the 30 provision of improved means for supporting compactly, roof propping mechanism.

Another object is the provision of a large 35 number of successively adjacent roof propping devices each provided with a long narrow base to distribute the pressure on the floor over a wide area, each roof propping device being individually movable to an advanced roof propping position in cooperation with other roof propping devices.

Another object of the invention is the 40 provision of improved mechanism for operating and controlling such roof propping device.

A further object of the invention is the 45 provision of a series of roof propping devices each provided with improved mechanism adapted to be connected to the next adjacent roof propping device to move the latter forward to a new location.

A still further object of the invention 50

is the provision of a system for carrying out a retreating method of mining in which entries are driven horizontally in opposite directions from a main entry and then removing by retreating operations the pillars 55 between such lateral or butt entries, and leaving the roof free to subside while controlling the subsidence of the roof so that continuous mining and loading operations will not be interfered with. The method 60 of mining contemplates the driving of lateral or butt entries from the main entry at one side of the latter while the retreating system of mining is carried on at the pillars between the butt entries on 65 at the other side of the main entry, thereby lessening the amount of apparatus being used at any one time for carrying on the mining operations.

Other objects of the invention will appear hereinafter, the novel features and combinations being set forth in the appended claims.

Referring to the accompanying drawings:

Fig. 1 is a diagrammatic view illustrating 75 my improved system and method of mining coal;

Fig. 2 is a diagrammatic view illustrating the method of handling a series of roof propping devices for controlling the subsidence of the roof;

Fig. 3 is an elevational view of one of the roof propping devices in position to control the subsidence of the roof as illustrated at the right hand portion of this 80 view;

Fig. 4 is an elevational view of a modified form of roof propping device with the inclined forward portion shown in Fig. 3, detached;

Fig. 5 is an elevational view of the type of roof propping device shown in Fig. 3;

Fig. 6 is an elevational view of a modification of Fig. 4;

Fig. 7 is a rear elevation of two adjacent roof supporting jacks showing the connections between them while in roof supporting positions;

Fig. 8 is a rear end elevation of a modified roof supporting jack particularly 100

adapted for location at the end of the series of roof jacks and adjacent an upright mine wall, this view also showing an additional connection to secure the movement to a new position of such modified roof supporting jack;

Fig. 9 is a sectional elevation of Fig. 10 on the line 9-9 looking in the direction of the arrows;

10 Fig. 10 is a plan view of the roof supporting mechanism shown in Fig. 7;

Fig. 11 is a sectional elevational view on the line 11-11 of Fig. 10 looking in the direction of the arrows;

11 Fig. 12 is a plan view of the adjacent roof supporting devices shown in Fig. 8; and

Fig. 13 is a sectional elevation taken on the line 13-13 of Fig. 12.

Referring to the left hand portion of 20 Fig. 1, I have shown multiple roof propping mechanism particularly adapted for the controlling of the subsidence of the roof over such portions where the mining of the coal has been completed, distant from the

25 places where the mining and loading of the coal is continuing. This multiple roof propping mechanism is preferably composed of separate individual long and narrow frames 14 each of which is provided 30 with a plurality or series of roof jacks as shown at 15 and 16 in Fig. 5. Each of the roof jacks comprises a plunger movable vertically in a hydraulic cylinder.

In Fig. 11 I have shown a cylinder 17 in 35 which is movable vertically a plunger 18 at the upper end of which is a roof engaging shoe 19. Ahead of the cylinder 17 is another cylinder 20 in which is movable vertically a plunger 21 at the upper end of which is a 40 roof engaging shoe 22. The roof engaging shoes 19 and 22 may be approximately square in plan view as shown in Fig. 10 and may also be of such a size as to be approximately of the same width as the frame 14 and therefore engage the next adjacent roof shoes 19' and 22', respectively, as shown in Fig. 10.

The flow of the fluid pressure medium to and from the cylinder 17 through the pipe 23, entering the bottom of the cylinder 17, as shown in Fig. 11, may be controlled by a valve 24 screw-threaded in the valve chest 25 for up and down movement by means of a manually operated crank 26 which is provided with a squared socket fitting on the upper squared end 27 of the valve stem 28. In the position shown in Fig. 11 the valve 24 is closed and the supply pressure from the pipe 29 to the pipe 23 is cut off. When, however, the valve stem 28 is 50 turned anti-clockwise by means of the crank 26, the valve 24 will be lifted and the pressure medium can flow from the supply pressure pipe 29 into the intermediate chamber in the valve chest 25 and thence into the pipe 23 to 55 the cylinder 17 forcing the plunger 18 up-

wardly and consequently forcing the roof engaging shoe 19 into contact with the roof. At such time the exhaust valve 30 remains closed.

When it is desired to release the roof prop 70 19 the valve 24 is closed and exhaust valve 30 opened. The opening of the exhaust valve is effected by turning the crank 26 and the vertical stem 31 in an anti-clockwise direction. The weight of the plunger 18 and the shoe 19 thereon will then cause the liquid to flow from the cylinder 17 through the pipe 23 and the exhaust passage 32' into the exhaust pipe 32. It will thus be seen that the valves 24 and 30 may be opened or closed independently of each other by means of the crank 26 having the squared socket fitting on the upper squared ends 27 and 33 of the valve stems 28 and 31.

The operation of the forward plunger 21 85 may be effected by controlling the flow of the pressure medium through the pipe 34 to and from the cylinder 20. This may be done by means of a set of supply and exhaust valves having vertical stems 35 and 36 provided 90 with upper squared ends 37 and 38, as shown in Fig. 10. By comparing Fig. 10 with Fig. 11, it will be seen that the horizontal passageways 29' 32' extend laterally cross the valve chest 25 for communication respectively with the supply pipe 29 and exhaust pipe 32. Leading upwardly from the passageways 29' and 32' are vertical openings or passageways 39 and 40, as illustrated in Fig. 11, these vertical passageways being controlled by valves at the lower ends of the vertical valve stems. It should also be noted that by means of this arrangement the forward hydraulic roof jack on each frame 14 may be controlled independently of the rear 105 hydraulic roof jack both in the application of the roof supporting mechanism to anchoring position and in the release of such roof supporting mechanism. The forward portion of the frame 14 of the narrow elongated 110 roof supporting mechanism is preferably inclined downwardly and forwardly, as shown at 41 in Figs. 3 and 11 so as to facilitate the withdrawal of the roof supporting mechanism in its roof propping position after the 115 material has subsided along definite lines as controlled by the roof supporting mechanism, and as shown in Fig. 3. Such forward inclined portion is desirable when it is necessary to have a large area in contact with the floor, particularly where the latter is of comparatively soft material. Furthermore, by providing the forward inclined portions 41, 120 downwardly and forwardly inclined planes are provided which tend to cause the fallen material to slide forward and not fill the spaces between the forward roof jacks. It is also preferred to have the inclined portions extend forwardly instead of rearwardly to obtain larger bearing surface on the floor 125 130

140

without taking up space where the mining operations are proceeding as shown at the left hand portion of Fig. 1.

However, larger bearing surface for the individual multiple roof supporting devices may be secured by lengthening the frame, as shown at 42 in Fig. 6 and in such event an additional roof jack 125 may be located at the forward end of such frame 42. When the floor is comparatively hard the multiple roof supporting mechanism may have a shorter frame as shown at 43 in Fig. 4. This structure is the same as that shown in Fig. 5 except that the forward inclined portion 41 is omitted and the forward end of the frame is provided with a vertical flat face approximately directly below the line of cleavage between the subsiding roof material and the body of the roof which is held in its original position by the roof jack 16.

I will now describe the mechanism on each multiple roof supporting device for shifting the position of the next adjacent roof supporting device to a new location. Each frame 14 is provided at its lower rear portion with a horizontal longitudinally extending cylinder 44 for receiving the plunger 45. To the rear end of the cylinder 44 is connected a pipe 46 for transmitting the pressure medium. As shown in Fig. 10, this pipe 46 is connected to the valve chest 25. In the same manner that the valves 24 and 30 control the supply and exhaust to the pipe 23, the valves at the lower ends of the valve stems 47 and 48 control the supply and exhaust to the pipe 46. Therefore by applying the crank 26 to the upper squared ends 49 and 50 of the valve stems 47 and 48 the supply pipe 29 may be connected through the pipe 46 to the cylinder 44 to move the piston or plunger 45 to the left as viewed in Fig. 11 and permit the frame 14 to be moved to the left when the plunger 45 is held stationary. That is to say, by opening the valve at the lower end of the valve stem 47 while the exhaust valve is closed, pressure may be exerted on the plunger 45 to move the same to the left. When the supply valve is closed and the exhaust valve is opened, the frame 14 and the cylinder 44 may be moved to the left while the plunger 45 is held stationary. By referring to Fig. 7 which is a rear end elevation of Fig. 10, it will be seen that the rear end of each of the plungers 45 is provided with a radial arm 51 which may occupy either a vertical position or a horizontal position. Each of the frames 14 is provided at one side thereof with a series of abutments in the form of recesses or notches 52 and 53 (Fig. 12) into which the radial arms are adapted to fit. In Fig. 7 the radial arm 51' is shown in interlocking position in the recess 52 of the next adjacent frame. After the roof prop shoes 19

and 22, shown in Fig. 10, have been released and the roof prop shoes 19' and 22' are still in roof propping position, the plunger 45' may have pressure exerted upon it through the pipe 46' to move the arm 51' to the left. By reason of the engagement of the latter with the frame 14 at the recess or notch 52, the elongated base frame 14 together with all the parts mounted thereon will be moved along the mine floor and the inclined portion 41 moved out from under the material which may have subsided thereon as illustrated in Fig. 3.

The additional recess or notch abutment 53 is for the purpose of permitting the series of roof supporting devices to be located in roof supporting positions along a diagonal line so as to control subsidence of the roof along such line instead of at right angles to the roof supporting devices. Therefore, even when such diagonal series of roof propping devices is used, they may be shifted individually by the arms 51, 51', etc., fitting, respectively, into the rear notches or recesses 53, 53', etc.

In order to automatically limit the rearward movement of a released roof propping device relatively to the anchored roof prop device from which the moving force is being exerted, I have provided a pipe 54 connected between the cylinder 44, as shown in Figs. 10 and 11, rearwardly of the forward end thereof and the exhaust passage 32' in the valve chest 25. During the first portion of the rearward stroke of the horizontal plunger 45 the forward end of the pipe 54 remains closed but after the plunger 45 has moved rearwardly a predetermined distance the forward end of the pipe 54 is uncovered or opened and the pipe 46 will thus be connected through the cylinder 44 in front of the plunger 45 to the exhaust pipe 54 and this will automatically effect stopping of the rearward movement of the plunger 45.

After a released roof propping device has been moved rearwardly a predetermined distance its vertical plungers may again be operated to roof supporting position so as to firmly anchor the frame 14. Now, when the next adjacent roof propping device is released from roof supporting position it may be moved rearwardly by the operation of the horizontal plunger of the next roof supporting device in the series. When this operation takes place the arm 51' remains in the notch 52. Therefore, when the frame 14 is moved rearwardly the horizontal cylinder 44 is moved rearwardly while the plunger therein is held stationary. This restores the horizontal plunger to its initial position relative to the cylinder in which it fits. From the foregoing it will be seen that the roof supporting device adjacent the worked-out portion of the series shown at

the left hand end of Fig. 1 may first be moved rearwardly by means of the horizontal hydraulic motor in the next adjacent roof supporting device. Then, when the first roof supporting device has again been anchored, the second roof supporting device may be released and the horizontal motor on the third device used to move the second device rearward. The second roof supporting device is then anchored in its new location and the rearward movement of the individual roof supporting devices continued until the whole series has been moved rearward.

15 After the horizontal motor on the last roof supporting device has been operated to move rearwardly, the next adjacent roof supporting device, additional mechanism must be employed to move rearwardly the last roof supporting device of the series which is the roof supporting device adjacent the upright face of the unmined mass shown at the lower left hand portion of Fig. 1.

In order to accomplish the rearward movement of such last supporting device of the series, I prefer to have such last supporting device of modified construction. This modified roof supporting mechanism is shown in side elevation in Fig. 6, in rear elevation in Fig. 8, in plan in Fig. 12, and in longitudinal sectional elevation in Fig. 13 in relation to the next preceding adjacent roof supporting device. An additional roof prop 125 is located on the forward 35 end of the frame 42 and the rearward portion of the frame is provided with a rearward extension 55 having a vertical bracket 56 in which is pivotally mounted an adjustable abutment 57. This abutment is pivoted to the support 56 by means of a pin 58 fitting into a cylindrical recess in the support 56 and a set screw 59 is provided to hold the abutment 57 in adjusted position. The abutment 57, upon release of the 40 set screw 59, may be swung on a vertical axis to the dotted line position shown at 57' in Fig. 12. When in this position the horizontal longitudinal motor in the frame 42 may be used to move the frame 14 rearwardly when the roof jacks on the latter are released and the radial arm 60 fits in the notch or recess 52 of the frame 14. Therefore, when the roof propping device, 45 next to the last in the series, is released, it may be moved rearwardly by the horizontal longitudinal motor of the roof propping device last in the series, and while the roof props of the latter are in anchored position.

Now, when the roof jacks of the roof propping device next to the last in the series, 50 are again anchored and the roof props of the last device in the series are released, the abutment 57 may be swung to the full line position shown in Fig. 12. Or, before the frame 14 is moved rearwardly the abut-

ment 57 may be swung to its full line position so that the rear end of the plunger 45 may be in such position that the radial arm 51 thereon may be turned up into engagement with the abutment 57. It will thus be seen that after the roof propping device next to the last in the series has been moved rearwardly and anchored, its longitudinal horizontal hydraulic motor may be relied upon to move rearwardly the roof propping device last in the series after the roof props of the latter have been released. This rearward movement of the last roof propping device in the series is effected by the horizontal motor of the next to the last device 55 in the series by reason of the connection of the radial arm 51 with the abutment 57. It can be seen that when the parts are in this relation and the plunger 45 is moved rearwardly in the roof propping device next to the last in the series, the frame 42 will be moved rearwardly and its roof props may then again be operated into roof propping position.

It should be noted that the roof propping device last in the series is provided with four sets of valves, one set for each of the three vertical hydraulic roof jacks and one set for the horizontal shifting hydraulic motor.

Referring now to Fig. 1 showing a system and method of coal mining to which the series of roof props herein illustrated is particularly adapted, it should be noted that back of the main entry is located a series of roof props 61 approximately the width of the entry and between those portions marked "Worked out" which are those portions from which the coal vein has been mined and the roof of foreign material allowed to subside. In order to reduce the cost of the mining apparatus in use at any one time, particularly the roof supporting mechanism, herein described, I wish to point out my improved method of mining which consists in first providing a main entry 62 and keeping the series of roof props 61 at the rear end thereof as shown in Fig. 1 and then providing a series of spaced-apart lateral or butt entries 63 and 64 and mining out sufficient 65 space for the series of roof supporting devices 65 and not beginning the formation of the lateral or butt entries 66 and 67 until the mining and loading machines 68 and 69 begin to mine the rear ends of the pillars 70 and 71.

Spaced-apart tracks 72 and 73 may be located along the main entry 62 and spaced-apart spur tracks 74, 75 and 76, 77 may be laid along the butt entries 63 and 64. Similar tracks 78, 79 and 80, 81 may be extended along the butt entries 66 and 67 as shown at the right hand portion of Fig. 1. As the mining and loading machines 82 and 83 proceed to mine the coal from the coal faces 130

84 and 85, the removable posts or roof jacks 86 may be placed wherever desired or deemed advisable. These temporary roof supports may be removed when the series 5 of roof subsiding supports 65 are moved rearwardly.

As the mining and loading operation by means of the mining and loading machines 68 and 69 proceeds to remove the pillars 70 10 and 71, the mining and loading machines 82 and 83 are proceeding to mine at the coal faces 84 and 85. The mine cars 87 and 88 for the mining and loading machines 68 and 69 may be located on switch track devices 89 and 90 so that an empty car may be moved from say the tracks 74 and 76 onto the switch tracks 89 and 90 and the loaded cars moved from the switch tracks 89 and 90 onto the tracks 75 and 77 for transportation to the main track 72. An intermediate track 91 may be provided for the movement of mine cars onto and off the adjacent tracks 74 and 75 without interfering with the mine cars traveling onto and off 25 from the tracks 76 and 77. Mine cars 92 and 93 may be located on switch tracks 94 and 95 which are similar to those designated 89 and 90. These switch tracks for the mine cars are preferably slidable along 30 the spaced-apart butt entry tracks and maintained in rail communication therewith.

In order to facilitate the transmission of power to the various mining and loading machines, I have provided a system of piping 35 which may carry either insulated electric wires for operating electric motors on the mining and loading machines, or such pipes may carry a fluid pressure medium for operating the mining and loading machines. 40 The main pipe is shown at 96 and various branch pipes 97 extend laterally from the main pipe 96.

At the rear end of the track 77 I have shown a special car 98 on which is diagrammatically shown a motor 99 supplied with power through the connection 100. At 101 I have diagrammatically illustrated a hydraulic motor connected at 102 to the series 45 of roof supporting devices which are particularly adapted for controlling the subsidence of the roof along definite predetermined lines. The connection between the hydraulic motor 101 and the series of said roof supporting devices may be made at the 50 pipes 29 and 32 shown in Fig. 12. It should be noted that the valve chest of each roof supporting device is connected by means of flexible connections and that the passageways 29' and 32' together with such flexible 55 connections constitute continuations of the supply and exhaust pipes throughout the whole series of roof supporting devices.

By the time that the mining and loading machines 68 and 69 have removed the pillars 70 and 71, the mining and loading ma-

chines 82 and 83 should have mined out such a space at the ends of the entries 66 and 67 and at the ends of the pillars 103, 104 as to afford sufficient space for the series of roof supports 65. As indicated by the broken lines 105 and 106, the butt entries 63 and 64 as well as the butt entries 66 and 67 are intended to be comparatively long so that by the time the pillars 70 and 71 have been removed the series of roof supporting devices 65 have been shifted several times toward the main entry and the roof allowed to subside several times, the last subsidence occurring a short distance from the main entry as determined by the series of roof supporting devices.

When the mining and loading machines 82 and 83 have mined out a sufficiently large space at the rear ends of the pillars 103 and 104, so as to be in readiness to make the return movement toward the main entry, the series of roof supporting devices 65 are loaded on mine cars and moved to the rear of the pillars 103 and 104 and set up in a series similar to that illustrated at the left hand end of Fig. 1. It should also be noted that as soon as the mining and loading machines 68 and 69 have completed the removal of the pillars 70 and 71, new butt entries will be started on the same side of the main entry but farther along in the direction of the arrow 107. While these new butt entries are being produced, the pillars 103 and 104 are being removed and when the latter are removed, new butt entries will be made on the same side of the main entry but farther along in the direction of the arrow 107. After the series of roof props 65 have been moved from the right hand side of Fig. 1 toward the main entry and the pillars 103 and 104 entirely removed, the series of roof props 61 may be shifted forward step by step while the tracks are being gradually taken up and the roof props 66 removed.

In Fig. 2 I have illustrated a method of controlling the subsidence of the roof in which a hauling machine 108 is employed for dragging the individual roof props from one end of a series 109 to the other end thereof. This hauling mechanism comprises a rope 110 which may be directed around a pulley at an anchorage 111 so that the individual roof propping devices may be pulled out longitudinally from under the subsided material 112. After the roof supporting device has been pulled out to the position shown in full lines in Fig. 2, the rope 110 may be disconnected from the pulley 111 and then the pull on the rope continued so that the roof supporting device will occupy the position shown in dotted lines 113. Continued pulling on the device will shift it to the position indicated at 114. Then, by extending the rope around

a pulley at the anchorage 115 the roof supporting devices may be shifted into position for location at the other end of the series 109 of roof supporting devices. The 5 series of roof supporting devices 116 may be shifted toward the body of coal 117 in the same manner that the series 63 of roof supporting devices in Fig. 1 are shifted step by step to the right toward the main entry. 10 It should be noted that 112 designates the roof which has subsided along the break line 118 which was determined by the series 116, whereas the break line 119 was determined by the series 109. The previous portion 15 of the subsided roof is illustrated at 120 and this subsidence was determined along the break lines 121. The next subsidence of the roof is to occur along the dotted line 122 of the series 109 and along 20 the dotted line 122 of the series 116. The area of the roof which must be freed before it will subside will depend upon various conditions, and therefore the series 109 must be lengthened and the series 116 moved forward 25 until sufficient area of roof will be freed to the left of the line 122 and back of the line 123 to cause subsidence by reason of the overhead weight of such roof, but when such subsidence does occur it will be 30 along the lines 122 and 123 because the roof supporting mechanism compels the roof to break along such lines. The roof over the entry 124 will remain intact because as the series 109 is moved along, the roof supports 35 86 are placed in position and spaced-apart in such manner as to hold up or support the roof.

Obviously those skilled in the art may make various changes in the details and 40 arrangements of parts herein disclosed without departing from the spirit and scope of my invention as defined by the claims hereto appended, and I wish, therefore, not to be restricted to the precise construction herein 45 disclosed.

Having thus fully disclosed an embodiment of my invention, what I claim and desire to have secured by Letters Patent of the United States is—

50 1. In a system of mining, the combination with a series of roof supports each having an elongated base adapted to engage the floor of the mine chamber over a comparatively large area, of means for connecting each roof support to the next adjacent roof support, and mechanism mounted on each roof support for shifting longitudinally the position of the next adjacent roof support by means of such connections.

55 2. In a system of mining, the combination with a jack comprising a base frame, of an additional jack comprising a base frame, power-operated mechanism on said first-named base frame, a connection between said power-operated mechanism and said

second-named base frame, and means for controlling said power-operated mechanism while said first-named jack is anchored to shift the position of said second-named jack while the latter is not anchored. 70

3. In a system of mining, the combination with a jack comprising a base frame, of an additional jack also comprising a base frame, a fluid pressure motor on said first-named base frame, said fluid pressure motor comprising a plunger movable relatively to said first-named base frame, a radial extension connected to the outer end of said plunger in position to fit into a notch on the base frame of said additional jack, and means for controlling the operation of said fluid pressure motor to cause said radial extension while fitting in said notch to move said additional jack to a new location. 75

80 4. In a system of mining, the combination with a plurality of jacks adapted to be arranged in series and each comprising a base frame having an abutment at one side thereof, of a plurality of motors one on each of said base frames, and a plurality of actuating devices one connected between each motor to the abutment on the next adjacent base frame. 85

90 5. In a system of mining, the combination with a series of roof supports each movable longitudinally relatively to the next adjacent roof support, of a plurality of motors one mounted on the frame of each roof support, a shifting connection between each motor and the frame of the next adjacent roof support, and means comprising flexible connections between each roof support and the next adjacent roof support for transmitting power to said motors without interfering with the shifting of the position of each roof support relatively to the next adjacent roof support. 95

100 6. In a system of mining, the combination with a plurality of roof supports adapted to be arranged in a series, of a plurality of fluid pressure motors one mounted on the frame of each roof support and each comprising a horizontal longitudinally movable plunger, a series of abutments one at one side of each of the frames of said roof supports, a plurality of radial arms one connected to the outer end of each of said plungers in position to engage the abutment of the next adjacent frame, means for transmitting the fluid pressure medium to said motors in multiple and comprising flexible connections between said frames to permit relative longitudinal movement thereof, and means for controlling the flow of the fluid pressure medium to said motors. 110

115 7. In a system of mining, the combination with a plurality of roof supports adapted to be arranged in a series and each comprising a base frame, of a plurality of shifting motors one on each of said frames, a plural- 120

ity of spaced-apart abutments on each frame, a plurality of arms each connected to its respective motor and adapted to be connected to either of the abutments on the 5 next adjacent frame, and means for controlling said motors individually.

8. In a system of mining, the combination with a plurality of jacks each comprising a base frame, of a plurality of fluid pressure 10 motors one on each of said base frames and each comprising a longitudinally movable plunger, a radial arm on the outer end of each plunger, a notch on each base frame in position to receive the arm connected to the plunger of the next adjacent frame when said arm is turned into such notch, and means for directing fluid pressure medium into said motors to effect 15 longitudinal movement of said plunger to cause said arm while in the notch to shift the position of the next adjacent base frame.

9. In a system of mining, the combination with an elongated rigid base frame 20 adapted to rest on and slide over a mine floor, of roof jack mechanism mounted on said base frame to move bodily therewith, means for controlling the operation of said roof jack mechanism, a motor comprising 25 a horizontally movable actuator mounted in said base frame for movement relatively thereto, a radial arm at the outer end of said actuator shiftably arcuately on the axis of said actuator to engage an adjacent roof 30 jack, and means for independently controlling the operation of said motor.

10. In a system of mining, the combination with an elongated base frame adapted 35 to rest on and slide over a mine floor, of a roof jack mounted on said frame in position to anchor the same, a motor comprising a horizontally movable actuator mounted on said base frame, a radial arm at the outer end of said actuator shiftably arcuately 40 on the axis of said actuator to engage an abutment in the mine, and means for controlling the operation of said motor to effect the sliding of said base frame over the mine floor when said jack is in released 45 position.

11. In a system of mining, the combination with a base frame adapted to rest on and slide over a mine floor, of means for anchoring said base frame, a fluid pressure 50 motor comprising a longitudinally movable plunger on said base frame, an arm connected to the outer end of said plunger to extend radially therefrom upwardly or laterally, and means for operating said motor 55 to effect movement of said plunger together with said arm relatively to said base frame.

12. In a system of mining, the combination with a narrow elongated base frame adapted to rest on and slide over a mine 60 floor, of a fluid pressure roof jack mounted

on said base frame, a fluid pressure motor comprising a plunger extending longitudinally of said base frame, means for connecting said plunger to a similar adjacent base frame, and means for controlling the operation of said roof jack and the operation of said motor independently of each other. 70

13. In a system of mining, the combination with an elongated base frame adapted to rest on and slide over a mine floor adjacent similar base frames, of a plurality of spaced-apart fluid pressure roof supports mounted on said base frame in tandem, a fluid pressure motor comprising a longitudinally movable actuator mounted on said 75 elongated base frame, a coupling device at the outer end of said actuator, means for controlling the operation of said roof supports, and independent means for controlling the operation of said fluid pressure 80 motor to secure longitudinal movement of said actuator relatively to said elongated base frame while the latter is anchored by said fluid pressure supports to effect shifting 85 of such adjacent similar base frames by 90 means of said coupling device.

14. In a system of mining, the combination with an elongated base frame having a forward downwardly inclined extension to form an inclined plane on its upper surface, of a plurality of fluid pressure roof jacks on said frame back of said inclined plane, a fluid pressure motor comprising a longitudinally extending actuator movable from the rear end of said frame, means for controlling the operation of said fluid pressure roof jacks, and means for controlling the operation of said longitudinal motor. 95

15. In a system of mining, the combination with a plurality of roof supports each comprising a base frame, of a longitudinally extending motor on one of said base frames, means between said motor and the next adjacent frame for laterally coupling 100 said next adjacent frame to said motor, and means for operating said motor to secure longitudinal shifting of such next adjacent frame. 110

16. In a system of mining, the combination with a plurality of roof supports arranged in series and each comprising a base frame, of a plurality of longitudinally extending motors one mounted on each of said base frames, and coupling devices between each motor and the next adjacent frame to 115 secure longitudinal movement of such adjacent frame upon the operation of said motor. 120

17. In a system of mining, the combination with a plurality of roof supports adapted to be arranged in a series and each comprising an elongated base frame, of a plurality of longitudinally extending motors one on each of said base frames, of a plurality of lateral coupling devices one adapt- 125 130

- ed to be connected between each motor and the next adjacent frame, means for controlling the operation of said motors individually from a common source of supply, and flexible connections between each frame and the next adjacent frame to permit longitudinal relative shifting of said frames while the connection of said motors to the common source of supply is maintained.
18. In a system of mining, the combination with a roof jack comprising an elongated narrow base frame adapted to rest on and slide over a mine floor, of a fluid pressure motor on said base frame comprising a horizontally and longitudinally movable actuator adapted to be connected to a similar adjacent jack, means for controlling the supply of fluid pressure to said motor to effect relative shifting of said jacks, and a connection between said motor and the exhaust to limit the stroke of said actuator.
19. In a system of mining, the combination with an elongated narrow base frame adapted to rest on and slide over a mine floor, of means for anchoring the same, a motor comprising a cylinder and a plunger of approximately the same diameter as the bore of said cylinder to make a water-tight fit therein a substantial distance back of the inner end of said plunger, a fluid pressure pipe connected to the rear end of said cylinder, and an exhaust pipe connected to said cylinder distant from the rear end thereof to limit the forward stroke of said plunger along said base frame to automatically stop the relative movement of said plunger and said base frame after the operation of said motor.
20. In a system of mining, the combination with an elongated rigid base frame adapted to rest on and slide over a mine floor, of a plurality of spaced-apart hydraulic roof jacks mounted on said base frame in tandem, and means comprising a pair of valves connected to each of said roof jacks to control the anchoring and release thereof, such control of each roof jack being independent of the control of the other roof jacks.
21. In a system of mining, the combination with an elongated rigid base frame adapted to rest on and slide over a mine floor and having vertical spaced-apart plane outer walls in parallelism, of a hydraulic roof jack mounted on said frame, a hydraulic motor comprising an actuator adapted to engage an abutment to effect the shifting of the said base frame and roof jack in a direction along the length of the base frame, and means comprising valve mechanism for controlling the operation of said roof jack and the operation of said hydraulic motor independently of each other.
22. In a system of mining, the combination with a plurality of jacks each comprising a base frame, of a motor mounted on one of said base frames and comprising a longitudinally movable actuator, and an abutment on the next adjacent frame movable into position to be engaged by said actuator to effect relative shifting of said frames.
23. In a system of mining, the combination with relatively shiftable roof jacks separately and independently operable but adapted to be located adjacent each other, of a motor on one of said roof jacks, and an abutment on the other roof jack movable into position to be engaged by said motor to push one of said jacks to a new position while the other is anchored.
24. In a system of mining, comprising a plurality of roof supports arranged in a series, of means on each roof support for longitudinally shifting the next adjacent roof support to a new location, and mechanism on the last roof support movable into position for engagement by the shifting means on the next to the last roof support to secure shifting of the last roof support while the next to the last roof support is anchored.
25. In a system of mining, the combination with a series of roof supports, of an abutment on the last roof support of the series movable on an upright axis into a lateral position, and a motor on the roof support next to the last in the series for engaging said abutment when in its lateral extending position to effect shifting movement of the last roof support in the series.
26. In a system of mining, the combination with a plurality of elongated base frames adapted to be arranged side by side in a series, of roof supporting mechanism on said series of base frames, motor means on each base frame, means for coupling each motor to the next adjacent base frame to effect longitudinal shifting of the latter, and an abutment in position on the last base frame of the series to be engaged by the motor on the next to the last base frame to effect shifting of the last base frame.
27. In a system of mining, the combination with a base frame, of roof supporting mechanism mounted thereon, a motor on said base frame comprising a longitudinally movable plunger, a radial arm connected to the rear end of said plunger, and an abutment mounted at the rear end of said frame for adjustment on an upright axis.
28. In a system of mining, the combination with an elongated base frame, of a plurality of spaced-apart hydraulic roof jacks mounted on said base frame, means for controlling the operation of said roof jacks, a longitudinally extending hydraulic motor comprising a rearwardly movable actuator mounted on said base frame, and an ad-

justable abutment mounted at the rear end of said base frame and movable into and out of position for engagement by a motor operated actuator on an adjacent frame.

5 29. In a system of mining, the combination with a series of individual long narrow base frames, of roof supporting mechanism individually mounted on said base frames, and power operated shifting devices on each 10 of said base frames and adapted to be connected to the next adjacent base frame to secure individual longitudinal shifting of said base frames one after another along said series of frames.

15 30. In a system of mining, the combination with elongated individual supporting frames adapted to rest on the floor of a mine chamber in a diagonal series relative to an upright wall in a mine chamber, of 20 roof propping mechanism mounted on said supporting frames, and power-operated mechanism connected between each frame and the next adjacent frame to secure successive shifting of said frames to adjusted 25 positions while such diagonal series relation is maintained.

31. In a system of mining, the combination with a series of roof-sustaining jacks adapted to be located closely adjacent each 30 other to form a predetermined line of support, of inclined extensions from said roof-sustaining jacks back of said line of support in position to receive material from the roof when the latter subsides back of such line 35 of support, and means for gradually shifting such line of support by moving the jacks individually away from the subsided material and moving such inclined extensions gradually from under such subsided material.

40 32. In a system of mining, the combination with a plurality of independently movable narrow elongated roof sustaining jacks, of means individual to each of said jacks 45 for controlling the operation thereof, and means comprising a hydraulic motor on one of the jacks and an abutment on the next adjacent jack for adjusting the relative positions of the adjacent jacks.

50 33. In a system of mining, the combination with a plurality of jacks, of means for operating said jacks, and mechanism for rigidly connecting the adjacent jacks to adjust the relative positions thereof.

55 34. In a system of mining, the combination with a series of individual, separate and independent jacks successively in sliding engagement with each other, of means for operating said jacks, and means rigidly 60 connecting the adjacent jacks for successively moving said jacks into a new series of alinement.

65 35. In a system of mining, the combination with closely adjacent parallel jacks, of means for operating said jacks, and hydrau-

lic mechanism for moving one jack into lateral alinement with another jack.

36. In a system of mining, the combination with a series of closely adjacent jacks substantially parallel with each other and in 70 substantial alinement laterally, of means individual to each jack for operating the same, and hydraulic means for moving the jacks one at a time into a new series in substantial 75 parallel alinement with each other and substantially in lateral alinement.

37. In a system of mining, the combination with a plurality of closely adjacent jacks parallel to each other, of means for operating said jacks, and means for pushing 80 the released jack into a new position.

38. In a system of mining, the combination with a plurality of jacks in lateral alinement and having roof engaging shoes closely adjacent each other, of means for operating said jacks, and mechanism for pushing 85 said jacks successively into new positions also in lateral alinement with each other.

39. In a system of mining, the combination with a plurality of elongated jacks each 90 adapted to rest on and slide over a mine floor and adapted to be arranged in a series to form a break line to control the subsidence of the roof, of means for operating the said jacks, and fluid pressure motor mechanism mounted on one jack and extending to another for adjusting the relative positions of adjacent jacks.

40. In a system of mining, the combination with a plurality of roof jacks adapted 100 to be placed in a series to form a break line to control the subsidence of the roof, of means for operating the said jacks, a hydraulic motor mounted on one of said jacks, a connection adapted to extend from said motor to another jack for shifting the relative positions of said jacks, and means for controlling the operation of said motor.

41. In a system of mining, the combination with a plurality of separate and independent closely adjacent jacks each having 110 an elongated frame adapted to rest on and slide over a mine floor, means for operating said jacks individually to anchored and released positions, a hydraulic motor mounted on each of said jacks, and means on each of said frames in position to be engaged by a hydraulic motor on the next adjacent jack for adjusting the relative positions of said jacks while one is anchored and the other 120 released.

42. In a system of mining, the combination with a plurality of separate and individual props adapted to be arranged side by side to form a long line of support, means 125 for operating said props, and hydraulic motor mechanism carried by the props themselves for changing the positions thereof to gradually vary the said line of support.

43. In a system of mining, the combina-

tion with a jack having a frame with spaced-apart lateral faces, of means for operating the same, a motor mounted on said jack between said frame, and means connected to 5 said motor and adapted to be rigidly connected to an anchorage for effecting shifting of the jack to a new position.

44. In a system of mining, the combination with a multiplicity of hydraulic mine 10 props adapted to be arranged in a series in a mine chamber to form a predetermined break line for controlling the subsidence of the roof, of hydraulic mechanism for expanding said mine props to anchored positions, and separate sets of valves for each 15 of the mine props for controlling the expansion and contraction of each prop individually.

45. In a system of mining, the combination 20 with a plurality of elongated base frames adapted to rest on and slide over a mine floor and each comprising an extension having an upper downwardly inclined surface, of roof jack mechanism back of said 25 inclined surface to effect a predetermined line of support when such plurality of frames are arranged adjacent each other, means on said frames for controlling the operation of said roof jack mechanism, and 30 means on one frame adapted to be connected to the next adjacent frame for effecting relative shifting of said frames to new locations.

46. In a system of mining, the combination 35 with an elongated rigid base frame adapted to move over a mine floor, of roof jack mechanism mounted on said frame to move bodily therewith, means for controlling the operation of said roof jack mechanism, a motor within the lateral walls of 40 said frame comprising an actuator movable relatively to said frame, and means adapted to extend from said actuator in position to engage an adjacent frame having roof jack 45 mechanism thereon.

47. In a system of mining, the combination 50 with an elongated base frame adapted to move over a mine floor and having outer walls adapted to fit in sliding engagement with adjacent elongated frames, of a hydraulic roof jack mounted on said frame, a hydraulic motor on said frame between 55 planes extending through said outer walls and comprising an actuator adapted to engage an abutment to effect the shifting of said base frame and roof jack in a direction along the length of said frame, and means comprising valve mechanism for controlling the operation of said roof jack and the operation 60 of said hydraulic motor independent of each other.

48. In a system of mining, the combination 65 with relatively shiftable elongated frames adapted to slide against each other along parallel paths, of roof jacks mounted

on said frames for separate and independent operation, a motor on one of said frames, and an abutment on the other frame movable into position to be engaged by said motor to push one of said frames with its jack to a new position while the other frame is anchored by its jack. 70

49. In a system of mining, the combination with a series of roof-sustaining jacks adapted to be located closely adjacent each 75 other to form a predetermined line of support, of extensions having upper downwardly inclined surfaces in position to receive subsided material at one side of said line of support, and means connected between an anchored jack and a released jack for shifting the position of the released jack. 80

50. In a system of mining, the combination 85 with a narrow elongated base frame adapted to move over a mine floor, of means for anchoring said base frame, a fluid pressure motor comprising a longitudinally movable plunger on said base frame between planes extending through the lateral walls of said base frame, and means for connecting said plunger to an anchorage in the mine to shift the position of said frame when released. 90

51. In a system of mining, the combination 95 with a narrow elongated base frame adapted to rest on and slide over a mine floor and having vertical spaced-apart parallel plane walls, of a fluid-pressure roof jack mounted on said base frame between 100 said walls, a fluid pressure motor comprising a plunger extending longitudinally on said base frame for operation between vertical planes extending through said spaced-apart walls, means for connecting said 105 plunger to a similar adjacent base frame, and means for controlling the operation of said roof jack and the operation of said motor. 110

52. In a system of mining, the combination 115 with an elongated base frame, of roof-supporting mechanism mounted thereon, a fluid pressure motor comprising a longitudinally movable actuator mounted on said frame, a coupling device at the outer end of said actuator, means for controlling the operation of said roof-supporting mechanism, and independent means for controlling the operation of said fluid-pressure motor to secure movement of said actuator relative to 120 said frame while the latter is anchored by said roof-supporting mechanism. 125

53. In a system of mining, the combination 125 with an elongated narrow base frame adapted to rest on and slide over a mine floor, of a roof jack mounted thereon, a fluid pressure motor on said base frame comprising a horizontal longitudinally extending cylinder with a plunger fitting closely 130 therein throughout substantially the entire

length thereof, means for controlling the supply of fluid pressure to said motor, and a connection between said motor and the exhaust to limit the stroke of said plunger.

5 54. In a system of mining, the combination with an elongated narrow base frame adapted to move over a mine floor, of means for anchoring the same, a fluid pressure motor comprising a cylinder and a plunger, a 10 fluid pressure pipe connected to said cylinder, and an exhaust pipe connected to said cylinder distant thereto and in position to limit the forward stroke of the plunger along said base frame to automatically stop 15 the relative movement of said plunger relatively to said base frame.

55. In a system of mining, the combination with a plurality of roof supports adapted to be arranged in a series, of means on 20 each roof support adapted to be connected to the next adjacent roof support to effect relative shifting of the roof supports, and an abutment on the last roof support of the 25 series to cooperate with the shifting means of the next adjacent roof support to secure shifting of said last roof support.

56. In a system of mining, the combination with a plurality of elongated base frames, of roof-supporting mechanism on 30 each of said base frames, a motor mounted on each base frame for connection to an adjacent base frame to effect relative shifting of the base frames, and an abutment on one of the frames in position to be engaged 35 by a motor on another frame to effect shifting of the frame having the abutment.

57. In a system of mining, the combination with two frames, of roof-supporting mechanism mounted on each frame, a motor 40 mounted on one of said frames and com-

prising a horizontally movable plunger, and an abutment carried by the other frame movable into position to be engaged by said plunger.

58. In a system of mining, the combination with a series of roof props adapted to be placed in lateral alinement to form a predetermined line of roof support to effect subsidence of the roof along such line, of means for operating the roof props, and 45 haulage mechanism for releasing the roof props individually and moving them into position for location at the other end of the series.

59. In a system of mining, the combination with a series of roof props adapted to be located closely adjacent each other in lateral alinement to form a predetermined line of support, of means for operating said roof props, and mechanism for removing a 60 roof prop from one end of the series into position for location at the other end of such series.

60. In a system of mining, the combination with a series of hydraulic roof jacks 65 arranged in lateral alinement to form a predetermined line of roof support, of a portable hydraulic pump for furnishing the fluid pressure supply to said hydraulic roof jacks, an electric motor for operating said 70 hydraulic pump, a truck for carrying said hydraulic pump and said electric motor, a transportation system for mine cars, and electrical supply connections associated with such transportation system and extended to 75 the electric motor on said truck.

In testimony whereof I have signed my name to this specification on this 19th day of June A. D. 1920.

EDMUND C. MORGAN.
